UNITED STATES PATENT OFFICE

ALBERT B. KRAUSE, OF PERTH AMBOY, NEW JERSEY, ASSIGNOR TO ANTON BREZINSKI, OF PERTH AMBOY, NEW JERSEY

ROPE CLAMP

Application filed November 15, 1932. Serial No. 642,697.

This invention relates to improvements in rope clamps, and has particular reference to a device for releasably connecting the ends of a rope or clothes line together.

5 The primary object of the invention resides in a clamping device especially adapted for connecting the ends of a clothes line together and which may be operated when necessary to take up any slack as it may 10 occur due to stretching of the line under the weight of articles supported thereon.

Another object of the invention is to provide a clothes line clamp in which the greater the pull upon the line, the greater will be 15 the clamping action produced thereby.

A further object of the invention is to provide a clothes line clamp which is simple and inexpensive of construction, and strong and durable for the purpose intended.

20 With these and other objects in view, the invention resides in the certain novel construction, combination and arrangement of parts, the essential features of which are hereinafter fully described, are particularly 25 pointed out in the appended claims, and are illustrated in the accompanying drawing, in which:

Figure 1 is a perspective view of the invention in use.

30 Figure 2 is a vertical longitudinal sectional view therethrough.

Figure 3 is a horizontal sectional view.

Figure 4 is a vertical transverse sectional view on the line 4-4 of Figure 2.

35 Figure 5 is a side elevational view of the clamping device showing the clamping cam at the limit of its movement to an inoperative position in full lines, and at the limit of its movement to operable position in dot and 40 dash lines.

Referring to the drawing by reference characters, the numeral 10 designates the improved clothes line clamp or connector in its entirety which includes a substantially 45

U-shaped casing 11 constructed of sheet metal and bent into the shape mentioned. Mounted in the side walls 12-12 of the casing 11 is a shaft 13, and pivotally mounted upon the shaft is a cam or eccentric clamp- 50 ing wheel 14. The opposite flat sides of the

clamping wheel 14 are formed with annular shoulders or flanges 15 which spaces the friction surface 16 on the periphery of the clamping wheel from the opposite side walls of the casing. Normally, the cam or clamping wheel 14 assumes a position shown in full lines in Figure 5 of the drawing as it will drop to this position under its own weight but for preventing the movement of the cam wheel past a dead center, a stop lug 16 is stamped inwardly from one of the side walls 12 of the casing. This lug engages one of the shoulders 15 of the cam wheel to limit the turning movements of the cam or eccentric wheel in opposite directions.

The bight portion 17 of the U-shaped casing is provided with an inwardly extending transversely disposed rib 18 and which is disposed to one side of the vertical axis of the cam wheel to produce a kink in the line when the clamping wheel is in clamping engagement in a manner presently to be explained. The opposite ends of the bight portion are bent or curved outwardly as at 19 to prevent the line to be clamped from 75 coming in contact with any sharp edges.

Carried by one end of the casing 11 is an attaching means in the form of an eye or loop member 20, the same being constructed of a single length of bendable wire and having its ends terminating in inwardly extending pintles 21 which are received in bearings 22 stamped from opposite sides of the casing. Thus the eye or loop member 20 is pivoted for swinging movement relative 85 to the casing 11.

In practice, the clamping device is especially adapted for use in connection with clothes lines where it is desired to connect two ends of a rope together in order to produce an endless line usually run over a pair of spaced pulleys. In such use, one end of the rope A is tied or knotted to the loop or eye 20 whereas the free end B is inserted into that end of the casing 11 opposite to that on 90 which the eye or loop 20 is carried. When inserting the free end B of the rope, assume that the cam or clamping wheel 14 is in the inoperative position shown in full lines in Figure 5. The operator pulls the free end 100

of the line B through the casing and exerts a downward pressure upon the clamping wheel 14. After the free end of the line has been pulled taut, it is released and the weight of the line or rope beyond the clamping device will cause the cam wheel 14 to automatically swing upwardly to clamping position as shown in Figure 2 of the drawing. When in this position, the bight portion 17 of the casing cooperates with the clamping wheel 14 to tightly grip the free end of the rope and the rib 18 causes the kinking of the rope adjacent to the point at which it is clamped thus assuring a positive connection between the free ends of the rope and the clamping device. Should it be desired to release the free end B of the rope, it is only necessary for the operator to pull upon the said free end to relieve the pull or tension upon the rope whereupon the cam wheel 14 will drop to the position shown in full lines in Figure 5 of the drawing. In the functioning of the device, it will be noted that the greater the pull upon the rope or line being clamped, the greater will be the clamping action produced thereby.

Although I have specifically stated that the device may be used for connecting two ends of a single rope, it will be appreciated that it may be used for releasably holding one end of the rope in which case the eye or loop member 20 is engaged with a hook or other supporting member.

While I have shown and described what I deem to be the most desirable embodiment of my invention, I wish it to be understood that various changes that come within the scope of the appended claims may be resorted to if desired.

Having thus described the invention, what I claim as new and desire to secure by Letters Patent of the United States, is:

1. A rope connector comprising a substantially U-shaped casing, attaching means carried by said casing, a shaft mounted in opposite side walls of said casing, a clamping wheel eccentrically mounted on said shaft, an annular shoulder formed on one side of said clamping wheel and concentric with respect to the axis thereof, and a stop lug stamped from the adjacent side wall of said U-shaped casing and positioned in the path of said shoulder for engagement thereby for limiting the turning movement of said clamping wheel in opposite directions to avoid the clamping wheel from reaching a dead center during its turning movement.

2. In a rope connector, a casing, attaching means carried by said casing, a clamping wheel eccentrically pivoted within said casing, a shoulder formed on one side of said clamping wheel, and a stop lug extending inwardly from the adjacent wall of said casing and positioned in the path of said shoulder for engagement thereby for limit-

ing the turning movement of said clamping wheel in opposite directions.

Signed at Perth Amboy, N. J. this 11th day of November 1932.
